CRUSHING METHOD

Edgar B. Symons, Hollywood, Calif., assignor to
Nordberg Manufacturing Company, Milwaukee,
Wis., a corporation of Wisconsin

Application February 10, 1934, Serial No. 710,591

3 Claims. (Cl. 83—46)

My invention relates to crushing methods and has for one purpose the provision of a new crushing method, operating on a new principle and effecting a crushing or breaking down of 5 larger particles to particles of small size with a minimum use of power and a maximum crushing speed and effectiveness. Another object is the provision of a novel method of impact crushing, whereby material moved along a given course, 10 for example by gravity, is caused to take a substantially instantaneous change of direction by impact. It may thereafter be arrested or caused to take a second change of direction by a further impact, giving two stages of reduction at a 15 single operation. Other objects will appear from time to time in the course of the specification and claims. One apparatus employed in the practice and process herein described and claimed, is illustrated, described and claimed in 20 my co-pending application No. 710,592, filed February 10, 1934.

I illustrate my invention more or less diagrammatically in the accompanying drawings, wherein—

25 Figure 1 is a diagrammatic side elevation of the device;

Figure 2 is a plan view;

Figure 3 is a vertical section through the impact portion of the device;

30 Figure 4 is a horizontal section on the line 4—4 of Figure 3;

Figure 5 is a section on the line 5—5 of Figure 3;

Figure 6 is a section on the line 6—6 of Figure 3.

Like parts are indicated by like symbols throughout the specification and drawings.

Referring to the drawings, I show a mechanism which may be used to practice my method, 40 though other means might be employed. I illustrate generally a device for elevating material, by conveyors or the like, for a free gravitational drop. It will be understood, however, that the propulsion of the material into the impact zone, 45 preferably obtained by a free gravitational drop, may be obtained by other methods or means of propulsion.

Referring to the drawings in detail, A generally indicates any suitable bin or source of supply of the material to be crushed. This indication is intended to be diagrammatic and clearly material from another conveyor, mine car or the like might be delivered to the device without the intermediary of a bin. For purpose of illustration, however, I illustrate the bin A and a

discharge chute or spout A¹, with associated forwardly extending side guide walls A². A³ illustrates any suitable conveying means for elevating the material to be dropped and crushed. I illustrate it as an endless conveyor passing about a lower pulley A⁴ and an upper pulley A⁵, which may if desired be driven through the drive pulley A⁶ with its belt A⁷ extending to any suitable power source. It will be understood that in this form of device, material discharged to the 10 conveyor A³ will move in the direction of the arrows upwardly along the conveyor in response to the movement of the conveyor through its closed path. The side walls A² serve to prevent any side escape of the material adjacent the point 15 of delivery from the spout A¹.

As the material passes upwardly along the conveyor A³ it is eventually discharged when the conveyor passes about the pulley A⁵, and drops down the vertical guide passage B. Assuming 20 that a mass of mixed material is discharged down the passage B, with dust, fines and the like, mixed in, it may be advantageous, in order to prevent waste of crushing power, to remove some of the fines. I may effect this by any suitable screening along the path of the conveyor A³ but find a practical solution to be the provision of air inlet and outlet apertures in the passage B, whereby a blast of air may be blown across the passage, transversely of the path of 25 drop of the material. This blast of air will carry off a substantial proportion of the dust or fines. I illustrate therefore, an inlet passage B¹, outlet passages B² and air propelling means B³, whereby the fine material may be carried off. It will 30 be understood, of course, that such passages are screened as at B⁴ or provided with mesh of such size that the particles desired to be crushed cannot escape. The use of this preliminary air cleaning in many circumstances is helpful but 35 the crushing method may be used without it.

Assume that the material to be crushed has been dropped by the conveyor A³ or by any other suitable means, into the top of the passage B, and that it is falling downwardly through said 40 passage. It will be understood that the passage B may be of such length that the material, if dropped on a fixed surface or anvil, would be moving fast enough to be crushed by the impact of its gravity accelerated drop. However, I obtain a more efficient crushing action by employing a moving impact member provided with one or more impact faces E⁰, the speed of movement and the angle of which, in relation to the drop 45 of the particles along the passage B, is such as 50 55

to cause an immediate stoppage and change of direction of the individual particles. This reduces to a minimum friction or abrasion of the impact surface, which would otherwise be very great, and cause a redirection of the particles, as shown in Figure 3, along a new direction of travel, at the end of which the particles may again be arrested by a second crushing impact against the plates G^6 . It will be understood that whereas preferably the speed of the particles as they move along the passage B is sufficient to cause their crushing or separation upon impact, I may rely only partially or in some circumstances little or not at all, upon the actual drop of the material and, by speeding up the impact member, may obtain a crushing separation by the rotation of the impact member through the falling stream of particles. It will be understood, however, that in the form shown in the present drawings the passage B may illustratively be considered to be of sufficient height to impart to the particles a velocity sufficient to cause their crushing in response to a stoppage at the end of their fall. The stoppage and change of direction causes a very substantial crushing or reduction in size of the particles and the particles are directed in a stream against the second impact member G^6 , where they receive a second impact, and thus are subjected to two stages of reduction in immediate succession.

In the practice of my method, the high gravity spout or chute B is an important factor, as it imparts to the falling particles a gravitational speed or acceleration sufficient to carry substantially all of the falling particles into the path of the impact members E^7 . The height of the chute B is so related to the peripheral spacing of the members E^7 and to the speed of rotation of the rotor, that all or substantially all of the particles are contacted by a full face impact, which prevents, or reduces to a minimum, the glancing blows against the upper edge of the impact members E^7 , which would otherwise prevent the substantially instantaneous and complete change of direction described elsewhere herein and diagrammatically illustrated by the arrows and the stream of particles shown in Figure 3.

Referring to the specific structure for obtaining this result, I provide a housing generally indicated as C , which includes the top portion C^1 , the rear wall C^2 , the forward wall C^3 , and side walls C^4 . C^5 indicates any suitable lower discharge chute which has an inclined wall C^6 and if desired an intermediate inclined wall C^7 .

The housing C may be fixed upon any suitable foundation D , as shown in Figure 5, and adjacent the housing are bases or supports D^1 for any suitable bearing systems D^2 in which rotate the ends D^4 of the shaft D^3 . D^5 is a drive pulley for the shaft D^3 which may be in communication with any suitable power source. I illustrate, for example, in Figure 2, the belt D^6 and the motor D^7 with its drive pulley D^8 . It will be understood that the shaft D^3 may be rotated, at a desirable speed or speeds, by the actuation of the motor D^7 . In order to minimize wear of the bearings and undue strain of the shaft and rotor, I have illustrated in Figure 5 the bearing members D^2 as being cushioned in rubber sleeves D^{15} mounted in split bearing housing D^{16} .

Secured to opposite sides of the rim D^{10} and the transverse ribs D^{12} are the side rings indicated as E . These rings may be channeled as at E^1 to receive a corresponding projection from the rim D^{10} . Each ring is shown as being formed of

three separate sections. These sections are secured to the rotor as by bolts E^2 and tie plates E^3 . The bolts E^2 pass through apertures in the rim D^{10} or the transverse ribs D^{12} and smaller bolts E^4 pass through the tie plates E^3 and the adjoining free end of one of the ring sections E and are connected at their inner ends with interior wear plates E^5 as shown for example in Figure 6. The impact plate or plates proper indicated as E^7 , rest on the forward inclined faces of the transverse ribs D^{12} . Each plate has a laterally extending lug E^8 at each side, which lugs are seated in corresponding slots E^9 in the side plates or rings E . In order to hold the wear plates in place, I provide wedges E^{10} which slide between the opposed edges of the side ring E as shown for example in Figures 3 and 6. There is a cam or wedge surface E^{11} against which a corresponding face of the wedge E^{10} rides and a tightening bolt or stem E^{12} is provided which may be drawn inwardly as by a nut E^{13} , the pin E^{12} passing through a boss E^{14} integral with the flange D^{10} . It will be understood that tightening up on the bolt E^{13} will draw the wedge E^{10} inwardly along the wedge surface E^{11} and cause the opposite side of the wedge E^{10} to lock against the lug E^8 of the impact plate E^7 . Not only is the impact plate thus firmly locked, but it is also easily removable for replacement or change. For example, the worn plate may be removed or the angle of the plate may be varied by putting in refill impact plates of varying angle. In such case the wedge E^{10} may also be replaced by a wedge of somewhat different shape or contour. In order to prevent material from packing in outside of the side plate or ring members E , I provide a circular flange E^{20} extending inwardly from each side wall C^4 of the housing. This structure will be clear for example from Figure 5. In order to provide ready access to the interior of the device I may have one or more removable walls, covers or the like. I illustrate for example, in Figure 3, the side wall portion E^{21} and top wall portion E^{23} , which are hinged as at E^{22} for ready removal as indicated in dotted lines.

It will be understood that as the material is dropped down the passage B and is engaged by the impact faces E^7 , it is caused to move generally laterally in the direction of the arrows as shown in Figure 3. The particles so delivered are initially crushed at the instant of impact and these smaller particles are delivered laterally at high velocity. I provide an additional breaker plate structure, generally indicated as G , for receiving this high velocity delivery of the smaller particles and for imparting to them, by impact of stoppage, a further crushing or grinding effect. In practice if the material is delivered in sufficient volume and sufficiently steadily down the passage B , the smaller particles will be delivered against the breaker plate structure G at such a speed as to build up something of a mass of material on the forward face of the breaker plate, and the smaller particles will tend to strike this mass of material, causing a very substantial grinding action of particle against particle as well as of impact against the plate proper. In order to effect this result I provide an arcuate supporting wall structure G^1 , herein shown as of two angular members, hinged as at G^2 for ready removal, cleaning or the like. It is normally held fixed as by the bolts G^3 one end passing through angles G^4 on the housing side wall C^4 . The structure G includes an upper angle G^5 through which the bolts G^3 pass, and which is in connection with the frame proper G^1 .

The impact plates proper G^6 , of which two are shown, are bolted to the angle or frame members G^1 for ready removability. It will be noted that the contour of the plate G^6 is generally arcuate, the purpose being to insure that there will be an immediate and complete stoppage of the material received by the plate and no glancing or angular blow. The speed of the rotor is such that all of the material impacted is caught by the impact faces proper E^7 . However, this material, owing to the speed of rotation, is delivered through somewhat varying paths and the impact plates G^6 are curved so that no matter what angle the material may take in relation to its previous travel down the passage B , it will take a path substantially vertical to the opposed portion of the impact plates. In effect the impact plates define an arc the center of which is the face of the rotor impact plate E^7 when it is aligned vertically with the passage B . It will be further understood that as one of the impact plates E^7 passes beyond the line of drop of the material along the passage B another impact plate crosses the stream before any of the material can drop far enough to engage the flange D^{10} . Thus every particle dropped down the passage B is actually caught by one of the impact plates E^7 and is thereby crushed by impact, and the crushed particles are thereby projected against the fixed impact plates G^6 for a further crushing and grinding against the plate G^6 and the mass of material on its surface. In other words, one charge of material delivered by an impact plate does not have a chance to drop away from the face of the plate G^6 before the next charge engages it.

All of the material separated drops down across the inclined surfaces C^6 or C^7 and thus passes from the crusher. Under many circumstances I find it desirable to employ this crusher in closed circuit, to screen out the finer material produced by the crushing operation and to return the oversize for a further crushing. This may be done by a variety of suitable mechanisms and for purpose of illustration, I illustrate but one. I may employ the endless conveyor H passing about the lower pulley H^1 and the upper pulley H^2 . It may be driven for example from the motor H^3 through the belt H^4 and the drive pulley H^5 , pinion H^6 and the gear H^7 . The material delivered from the crusher, in the form of the device shown in Figures 1 and 2, is picked up by the belt H and carried to a distribution member H^8 whence by chutes H^9 , H^{10} it may be delivered to screens H^{11} , H^{12} . The oversize from these screens is delivered by discharge chutes H^{13} , H^{14} to the up-conveyor A^3 . The screened material may be delivered to a different conveyor H^{15} and thus escape from the crushing circuit.

It will be realized that whereas I have shown a practical and operative device for carrying out my method, nevertheless, I wish the description and drawings herein to be taken as in a real and broad sense illustrative and diagrammatic rather than as limiting me to the specific mechanism herein shown or to the specific sequence of steps described. My method may be practiced with a variety of mechanisms without departing from the spirit of my invention.

The use and operation of my invention are as follows:

Most broadly stated, my method is directed to advancing or moving a stream of material, by gravity or otherwise into an impact zone, and there causing the substantially instantaneous

stoppage and change of direction of each particle, by moving across the stream of falling or moving material an impact member or a succession of impact members. The impact member or members are set at such an angle to the falling stream and are moved at such a speed in relation to the speed of the falling particles as to effect a practically instantaneous stoppage and change of direction of each particle.

Referring to Figure 3, the impact members E^9 are rotated across the path of falling particles and direct them against the impact plate G^6 . Their speed of movement is sufficient to effect a further reduction or breakage at that point. The plate G^6 is curved because the path of movement of the impact directed material from the member E^9 varies in angle as the impact member moves through the falling stream. All the material engages the impact plate G^6 directly, and with no sliding or angling. This being true of the engagement of the particles against E^9 as well as G^6 , abrasion or wear of the plate is reduced to a minimum. The rotation of the shaft D^3 is at such a rate that none of the falling particles can fall through the ring defined by the rotation of the members E^9 without being impacted by one of them. None of the particles can drop down onto the portion D^{10} of the rotor. Furthermore, the successive increments to particles delivered against the plate G^6 may come so rapidly as to build up a species of sheet or mat of material. In other words, the particles which have already been broken by impact against the surface E^9 are directed into the mass of particles resting against or falling across the surface of the plate G^6 . The result is not merely an impact breakage against the plate G^6 , but also a grinding of particle against particle which causes a maximum separation important for fine crushing.

Whereas my method may very efficiently be employed in connection with a freely falling column of material, it will be understood that it may be practiced by other mechanisms. For example, the material might be allowed to slide down an inclined plate into the impact zone, or it might be moved or thrown into the impact zone by other means. The particular details of the mechanism are therefore given not to limit the method but to indicate some one mechanism which can be practically used in practicing the method.

I claim:

1. The method of limiting abrasion in impact crushing which includes delivering the particles to be crushed in an unconsolidated stream along a predetermined and laterally limited path and at a predetermined rate of speed, rotating a plurality of impact members having faces rearwardly inclined to the direction of movement of the particles so fed, and lying in planes parallel with their axis of rotation, through a predetermined path intersecting the path of feed of the particles, at speed sufficient to crush the particles, and which speed is effective, in connection with the angle of said impact members and the speed of feed of the particles when struck, to cause an instantaneous change of direction of the particles, without slippage of the particles across the surfaces of the impact members, and thereby projecting the particles entirely out of the path of movement of the impact members along a path generally at right angles to the faces of said impact members, and thereafter removing 75

said particles along a path remote from said impact members.

2. The method of limiting abrasion in impact crushing which includes delivering the particles to be crushed in an unconsolidated stream along a predetermined and laterally limited path and at a predetermined rate of speed, rotating a plurality of impact members having faces rearwardly inclined to the direction of movement of the particles so fed, and lying in planes parallel with their axis of rotation, through a predetermined path intersecting the path of feed of the particles, at speed sufficient to crush the particles, and which speed is effective, in connection with the angle of said impact members and the speed of feed of the particles when struck, to cause an instantaneous change of direction of the particles, without slippage of the particles across the surfaces of the impact members, and thereby projecting the particles entirely out of the path of movement of the impact members along a path generally at right angles to the faces of said impact members, and terminating said projection by a secondary impact delivered by a fixed member the surface of which is normal to the path of movement of said impacted particles,

and thereafter removing said particles along a path remote from said impact members.

3. The method of limiting abrasion in impact crushing which includes delivering the particles to be crushed in an unconsolidated stream along a predetermined and laterally limited path and at a predetermined rate of speed, rotating a plurality of impact members having substantially flat faces rearwardly inclined to the direction of movement of the particles so fed, through a predetermined path intersecting the path of feed of the particles, at speed sufficient to crush the particles, and which speed is effective, in connection with the angle of said impact members with respect to the direction and the speed of feed of the particles when struck, to cause an instantaneous change of direction of the particles, without slippage of the particles across the surfaces of the impact members, and thereby projecting the particles entirely out of the path of movement of the impact members along a path generally at right angles to the faces of the impact members, and thereafter removing said particles along a path remote from said impact members.
